UNITED STATES PATENT OFFICE.

THEODORE A. GERBIG, OF ARCHBALD, PENNSYLVANIA.

DESIGN FOR A BADGE.

SPECIFICATION forming part of Design No. 26,420, dated December 22, 1896.

Application filed October 21, 1896. Serial No. 609,620. Term of patent 14 years.

To all whom it may concern:

Be it known that I, THEODORE A. GERBIG, a citizen of the United States, residing at Archbald, in the county of Lackawanna and State of Pennsylvania, have invented and produced a new and original Design for Badges, of which the following is a specification.

My design for a badge is illustrated in the accompanying drawing. In the background there is a flag or banner 1. At the upper end of the banner there is an ornament consisting of two gavels 2, having their handles crossed, and in front of these is a panel 3, having at each end a folded extension 4, all of these parts being symmetrically arranged. Suspended from the panel 3, by chains 13, is a second panel 5, which is generally rectangular, but has its lower and upper edges convexly curved. At the ends of the panel 5 are semicircular extensions 6. At the lower end of the banner and detached from the panels

3 and 5 is a pendant 7, consisting of a shield 8, having a panel 9 at its upper part and a vertically-striped field 10 on its lower part. Upon the field is an open book and below the book the representation of two hands clasped. There is a representation of a draped flag 11 at each side of the shield, the lower ends of the flags extending in wavy lines below the shield. Directly above the shield and between the flags is an eagle 12, having in its claws three arrows pointing to the left and an olive branch inclined to the right.

What I claim is—

The design for a badge substantially as shown and described.

In testimony whereof I affix my signature in presence of two witnesses.

THEODORE A. GERBIG.
